(57) **CLAIM**

The ornamental design for a brooder box, as shown and described.

DESCRIPTION

FIG. 1 is a front perspective view of a brooder box showing our new design;

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

The broken line is for the purpose of illustrating portions of the brooder box and forms no part of the claimed design.
